[57] CLAIM

The ornamental design for a parrot in flight air freshener, as shown.

DESCRIPTION

FIG. 1 is a perspective view of a parrot in flight air freshener embodying my design;

FIG. 2 is a front side elevational view of said air freshener;

FIG. 3 is a rear side elevational view of said air freshener;

FIG. 4 is a left end elevational view of said air freshener;

FIG. 5 is a right end elevational view of said air freshener;

FIG. 6 is a top plan view of said air freshener; and,

FIG. 7 is a bottom plan view of said air freshener.
